(57) **CLAIM**

The ornamental design for a camera weather shield, as shown and described.

DESCRIPTION

FIG. 1 is a top, front and right side perspective view of a camera weather shield showing my new design;

FIG. 2 is a top, rear and left side perspective view thereof; and, FIG. 3 is a bottom plan view thereof.

The portions of the camera weather shield in broken lines are shown for illustrative purposes only and form no part of the claimed design.
